UNITED STATES PATENT OFFICE.

WENDELL S. MERICK, OF CHICAGO, ILLINOIS.

IRONING MACHINE.

Application filed September 2, 1921. Serial No. 497,857.

To all whom it may concern:

Be it known that I, WENDELL S. MERICK, a citizen of the United States, residing at Chicago, in the county of Cook and State of Illinois, have invented certain new and useful Improvements in Ironing Machines, of which the following is a specification.

This invention relates to ironing machines.

It will be explained as applied to an ironing machine having a motor driven rotatable pressing cylinder and a heated, non-rotatable pressing shoe. The cylinder and shoe are relatively movable toward and from each other in assuming pressing and non-pressing positions.

With the ordinary ironing machine the shoe will not burn the padding on the cylinder as long as the cylinder is in motion. However, if for any cause, the cylinder stops while the heated shoe is in contact therewith, the padding is very apt to burn, resulting in its destruction and the creation of a dangerous fire hazard.

One of the objects of this invention is to provide an improved ironing machine.

Another object is to provide an ironing machine wherein the shoe and cylinder are automatically separated whenever the cylinder ceases to turn or appreciably decreases its rate of rotation.

Another object is to provide an ironing machine wherein the shoe and cylinder, when brought together to pressing position, are automatically held in such condition until the rate of rotation of the pressing cylinder decreases.

Other objects and advantages will herein-after appear.

An embodiment of the invention is illustrated in the accompanying drawings, wherein—

Fig. 1 is a front perspective of the entire machine.

Fig. 2 is a front elevation thereof, partly in section.

Fig. 3 is an end elevation, partly in section showing the machine in pressing position.

Fig. 4 is a top plan of a portion of the foot lever latch and tripping mechanism.

Fig. 5 is an enlarged end view of the tripping mechanism.

Fig. 6 is an enlarged end view of the trip.

Fig. 7 is a side view thereof.

Fig. 8 is an enlarged view showing the relation of the trip and latch in releasing position, and

Fig. 9 is an enlarged view showing the relation of the trip and latch in locking position.

The ironing machine has a rotatable pressing cylinder 1 and a curved pressing shoe 2.

The shoe is rigidly connected at opposite ends to end frames 3 and 4, respectively. The end frames may be made of suitable material such as pressed steel or cast iron. The shoe may be heated by any suitable means.

Cylinder 1 is carried on a shaft 5 which is journaled, at opposite ends, in brackets 6 and 7. Brackets 6 and 7 are journaled on and supported by a shaft 8 which extends between and is journaled to end frames 3 and 4. The cylinder is rotated by a motor 9 through a vertical shaft 10 and worm and gear trains 11 and 12. The worm and gear trains and shaft 11 are housed in bracket 6. Motor 9 is carried by a pair of brackets 13 and 14 rigidly bolted to shaft 8 so as to be moved therewith. The motor is journaled to brackets 13 and 14 so that it is rotatably mounted as a whole for a purpose to be hereinafter explained.

Thus when shaft 8 is rocked, as will be hereinafter described cylinder 1 is moved into and out of pressing position relative to shoe 2 and the motor is also rocked so that the driving gear trains remain in proper engagement.

Shaft 8 has an arm 16 secured thereto at each end. Each arm 16 has a socket 17 pivotally attached to its outer end. Each socket 17 has a rod 18 slidably passing therethrough. Rods 18 are threaded at their lower ends and slidably pass through sockets 19. Sockets 19 are respectively pivotally carried on one arm of a pair of bell crank levers 20. A pin 21, passing through each rod 18, and cooperating with the corresponding socket 17, anchors one end of the rods. The threaded end of each rod has an adjusting nut 22 thereon which cooperates with the corresponding socket 19 to regulate the effective length of the respective rod.

Bell crank levers 20 are rigidly secured to a shaft 25 which is journaled in end frames 3 and 4 and have a foot rail 26 pivotally connected thereto. Thus the depression of rail 26 oscillates bell crank levers 20 and,

2

through rods 18 and arms 16, oscillates shaft 8. The oscillation of shaft 8 rocks the motor and pressing cylinder as hereinbefore described. When rail 26 is depressed the cylinder is made to approach the shoe and when the rail is raised the cylinder moves away from the shoe.

The cylinder is held in pressing position when it has been moved thereto.

- 10 An arm 27 is rigidly secured to shaft 25 so as to move therewith. Arm 27 is pivotally connected to a bell crank lever 28. One arm of lever 28 is pivotally connected to the front of rail 26 by a link 29. The other arm of lever 28 is provided with ratchet teeth 30. Ratchet teeth 30 cooperate with a latch 31 secured to a shaft 32 which is journaled in end frames 3 and 4. Latch 31 is a substantially L shaped arm journaled 20 in a disc 33 carried on shaft 32.

Latch 31 is connected to a link 34 which is connected to one arm of a bell crank lever 35 on a shaft 36. Shaft 36 is journaled in end frames 3 and 4. The other arm of lever 25 35 is connected to the frame of motor 9 by a link 37.

The operation of the machine is as follows:

- 30 Depression of rail 26 moves the cylinder into pressing position as previously explained. The rotation of motor 9 causes the same to move as a whole in the journals of brackets 13 and 14. This slight movement or torque of the motor pulls link 37 and rocks bell crank lever 35. The rocking of bell crank lever 35 moves latch 31 so that it is in a position to engage and hold one of the ratchet teeth of lever 28 (see Fig. 9). Thus when the rail is depressed 40 while the motor is rotating the cylinder the teeth of the ratchet on lever 28 are engaged and held by latch 31. While the motor is running the cylinder may be released and moved from pressing position by the operator slightly tilting rail 26. This tilting of the rail rocks lever 28 and its teeth are disengaged from latch 31.

45 As long as the motor is running with sufficient speed to create a pulling force or torque sufficient to rock and hold latch 31 in locking position the cylinder is held in pressing position until released by the operator.

50 However, should the speed of the motor decrease, because of interruption of the circuit thereto or from other causes, to a point where its tendency to rotate or its torque will not create sufficient pull to hold latch 31 in locking position the latch rocks back 55 to the position shown in Fig. 8; lever 28

is released and the cylinder is automatically unlocked and assumes nonpressing position.

By the use of this arrangement the pressing cylinder and shoe are automatically caused to separate when the motor speed 65 and consequently the cylinder speed falls below a predetermined amount.

Having described my invention what I claim as new and desire to secure by Letters Patent, is:—

70 1. An ironing machine having a pressing shoe, a rotatable pressing cylinder, means for moving the cylinder and shoe relatively nearer together to pressing position and holding the same in such condition, and means for causing the separation of shoe and cylinder when the cylinder rotation decreases.

75 2. An ironing machine having a pressing shoe and rotatable cylinder which are moved relatively nearer together to pressing position, means for rotating the cylinder, and means for automatically causing the separation of cylinder and shoe upon a decrease in the rate of rotation of the cylinder.

80 3. An ironing machine having a pressing shoe and a rotatable cylinder which are adapted to be moved relatively nearer together to pressing position, manually controlled mechanism for moving the shoe and cylinder relatively nearer together, a latch for locking the mechanism in a position to hold the cylinder and shoe together, means for rotating the cylinder, and means under the control of the first mentioned means and 85 acting automatically to release the latch and allow separation of the cylinder and shoe when the speed thereof decreases.

85 4. An ironing machine having a stationary heated shoe, a rotatable cylinder adapted to be moved into and out of pressing relation to the shoe, a motor for rotating the cylinder, means for holding the cylinder in pressing position as long as the motor speed is maintained, and means for causing the cylinder to move to non-pressing position whenever the motor speed decreases below a predetermined amount.

90 5. An ironing machine having a pivoted rotatable cylinder, a relatively stationary shoe, means for rotating the cylinder, manually actuated mechanism for moving the cylinder into pressing position relative to the shoe, a latch for holding the cylinder in pressing position, and a release for the latch controlled by the rate of rotation of the cylinder.

95 In testimony whereof I hereunto subscribe my name.

WENDELL S. MERICK.
